UNITED STATES PATENT OFFICE

ANTHONY GODLEY, OF WEST FRANKFORT, ILLINOIS

AUTOMATIC MINE DOOR.

Application filed June 4, 1924. Serial No. 717,757.

To all whom it may concern:

Be it known that I, ANTHONY GODLEY, a citizen of the United States, residing at West Frankfort, in the county of Franklin and State of Illinois, have invented certain new and useful Improvements in an Automatic Mine Door, of which the following is a specification.

This invention relates to an improved mine door, and has particular reference to a closure of this class which is automatic in operation.

My principal aim is to provide a closure of the above named class which is automatically opened by a car when the latter approaches the closure, the doors of the closure beginning to open when the car reaches a predetermined distance or point on opposite sides thereof and being fully opened when the car reaches the closure to permit unobstructed passage of the car.

One of my objects is to provide a structure of this class which is positive in operation, the doors being automatically opened by means controlled by the car as it approaches the doors from either side, and being automatically closed after the car has passed beyond the operating means on the other side of the closure.

An important feature of the construction which I select in carrying out the invention is the rigidity of parts accomplished the practical arrangement, from construction and bracing thereof.

Other features and advantages of the invention will become apparent from the following description taken in connection with the accompanying drawings.

In the accompanying drawings forming a part of this specification and in which like numerals are employed to designate like parts throughout the same:

Figure 1 represents a top plan view of a section of a mine car track showing my improved automatic door or closure in association therewith.

Figure 2 is a front elevation of the improved closure and its actuating means.

Figure 3 is an end elevation thereof.

Referring to the drawings in detail, it will be seen that the closure frame is designated generally by the reference character 1. The frame is of a size to permit free passage of the car therethrough and is rectangular in outline, suitable angle irons or the like 2 being placed in the corners there-

of to brace the side bars. The closure is composed of a pair of duplicate sheet metal doors 3 integral with and extending inwardly from posts 4 provided at the outer ends thereof. These posts are journaled for rotation in suitable bearings 5 secured to the vertical side bars of the frame. If desired, the bearings may simply be in the form of eye bolts as shown in the drawing. Each door is provided with vertically spaced horizontal bracing strips 6 and at the centers are supplemental bracing strips 7.

In practice, the closure is mounted at any suitable point along the track in the mine and is supported in the customary or in any other appropriate manner. The rails R of the track pass beneath the bottom edges of the door, and disposed alongside of the rail on one side and positioned on opposite sides of the closures are supplemental car actuated rails 8. These rails may be fifteen or twenty feet in length and they are suitably pivoted and anchored at their outer ends as indicated at 9. The inner ends of the rails 8 terminate adjacent and beneath the closures and are active on operating means for opening and closing the doors when the car approaches the door from either side.

Although the operating means could be of some other construction, I prefer to employ a transversely disposed operating bar 10 which extends beyond the vertical sides of the frame. As seen more clearly in Figure 1, the intermediate portion of the operating bar is offset and the ends thereof are provided on sides opposite to each other with rack teeth 11. Pinions 12 are fixed to the lower depending ends of the aforesaid posts 4 and the rack teeth at the opposite ends of the bar mesh with these. It is obvious that with this arrangement, when the bar is moved cross wise of the track, the pinions are rotated and as soon as these are rigidly connected to the door posts, the latter are likewise rotated and the doors, which they carry, are swung open. As it is essential to apply movement to the operating bar from the aforesaid supplemental rails 8, suitable connections are provided. In the present instance I provide two substantially C-shaped brackets 13, the horizontal upper arms of which are fixed to the inner spaced ends of the supplemental rails, the lower arms of which are attached to portions of

the operating bars therebeneath. It is evident that by providing this rigid connection between the inner ends of the rails 8, when these inner ends are swung outwardly 5 away from the rigid rail of the track, the aforesaid rack bar will be moved and the doors opened. In order to return the parts to their normal positions after the car has passed a predetermined point on the opposite side of the closure, I employ a comparatively strong coiled spring 14 which is attached at one end to the rack bar and is anchored at its opposite end to any suitable stationary part. In the present instance it 10 is attached to the under side of a platform or cover board 15 which extends over the operating parts of the device to protect them. If desired, a suitably designed brace 15 may be disposed between the door frame 16 and an adjacent tie as seen more clearly in Figure 3.

It is understood that in use, the flanges of the wheels of the car will pass between the supplemental pivoted rails 8 and the stationary rail. Hence, as the car approaches the closure from either side, the supplemental rails will be swung outwardly upon their pivots and in so doing, the aforesaid rack bar will be actuated to operate the doors. The doors will open gradually, yet rapidly, and the spring will function at this time to insure smooth operation. Assuming that the car is traveling in a direction from right to left, it is clear that before it approaches the closure, the doors will be fully opened and they will remain open until the car has passed beneath the frame, at which time they will gradually close until the car 20 has passed beyond the pivot point of the

supplemental rail on the left hand side of 40 the doors. With this arrangement rapid closing or slamming of the doors is overcome.

It is thought that the foregoing description when taken in connection with the 45 drawing will suffice to enable the reader to obtain a clear comprehension of the invention. For this reason, a more lengthy and detailed description is deemed unnecessary.

Although I have shown and described a 50 specific structure and arrangement of parts for carrying out the invention, I wish it to be understood that minor changes coming within the scope of the subjoined claim may be resorted to if desired.

Having thus described the invention, what I claim is:—

In an automatic mine door, a supporting frame adapted for transverse disposition across a track, doors having posts at their outer ends pivotally mounted from said frame, pinions rigidly fixed to the lower ends of the door posts, a rack bar extending between said posts, the rack teeth meshing with the teeth of the respective pinions, a 55 return spring attached at one end to the rack bar and anchored at its opposite end to a stationary part of the structure, a supplemental car actuated rail adapted for disposition alongside of a main rail of the 60 track, the supplemental rail being pivoted and anchored at its outer end, and a rigid connection between the inner free end of said rail and said rack bar for imparting 65 movement to the latter when the rail is 70 swung upon its pivot by the car.

In testimony whereof I affix my signature.

ANTHONY GODLEY.
